UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

SHANK-BEATING MACHINE.

1,181,328.

Specification of Letters Patent.

Patented May 2, 1916.

Application filed August 9, 1911. Serial No. 643,211.

To all whom it may concern:

Be it known that I, RONALD F. McFEELY, a citizen of the United States, residing at Beverly, in the county of Essex and State 5 of Massachusetts, have invented certain Improvements in Shank-Beating Machines, of which the following description, in connection with the accompanying drawings, is a specification, like reference characters on 10 the drawings indicating like parts in the several figures.

This invention relates to machines for use in the manufacture of boots and shoes and more particularly to a machine for shaping 15 the shank portion of the shoe to conform the sole to the transverse contour of a thick shank stiffener applied to the bottom of the innersole of a lasted shoe. The usual method of shaping the shank portion of the 20 shoe consists in beating or pounding the shank portion of the sole with a hand hammer to reduce the sole to correspondence with the contour of the stiffener. When operating upon shoes which are provided with 25 the "cottage roof" form of stiffener, that is, a stiffener having a sharp ridge extending along the longitudinal median line of the stiffener, it is especially hard to conform the sole to the stiffener by the hand hammer. 30 Stiffeners of this type are extensively used in the manufacture of women's turn shoes, and the shank of such a shoe, when conformed to the stiffener, slopes toward the sole edge upon each side of the median 35 line. In performing this operation with a hand hammer considerable care has to be used that the shoe is not injured by too violent or misdirected blows which would tend to break down the stiffener or be liable 40 to strain the sole attaching stitches. This method is also slow and requires considerable time for what is a minor operation.

One object of the present invention is to provide mechanical beating means which 45 will conform the shank portion of the sole to the stiffener in such a manner as to obviate the above enumerated disadvantage of the hand method.

An important feature of this invention 50 consists in the combination with a support by which the shoe is movable to present either side of the shank alternatively in a se-

lected plane, of a beater arranged to strike the shoe with a slight inward component of its movement directed away from the edge 55 and means for actuating the beater to do its work.

Another feature of the invention consists in means for so operating the beating means that it is rapidly vibrated and operates on 60 the shoe with a succession of uniform blows. A resilient connection between the beating means and the operating means gives a yielding blow to the beater or hammer and compensates for the variations of the sole 65 at the shank. This yielding connection, preferably, as herein shown, comprises a piston and cylinder interposed between a vibrating hammer and a crank shaft on the machine. Resilient material, preferably of 70 slight compressibility, is located in the cylinder of the said connection and acts on the reciprocating piston in such a manner that a connection between the beater and its actuator is established, which, while substantially positive, is yielding enough for the 75 purposes above set forth.

The shoe is supported during the beating operation by a jack which is so mounted 80 that the shoe may be moved in such manner that the portion being acted upon may be maintained always in substantial alignment between its point of support and the beating means. The jack possesses certain 85 features of novelty which form part of this invention.

These and other features of the invention, including more important details of construction and combinations of parts will be explained in the following description and 90 pointed out in the claims.

Figure 1 is a side elevation of a shank beating mechanism embodying the present invention; Fig. 2 is a side view in elevation showing the position of the hammer on 95 the shoe in operation; Fig. 2^a is a sectional detail; Fig. 3 is a perspective view of the piston and cylinder connection; Fig. 4 is a front view of the upper portion of the machine; Fig. 5 is a detail of the heel post; 100 Fig. 6 is a detail of the actuating means.

Referring to the drawings, a column 1 carries at its upper part a head 3. This head is formed with two uprights 4 in which

is journaled the crank shaft 5. The crank shaft 5 has fast on its outer end a disk member 6, Fig. 4, which co-operates, as a friction member, with a loose pulley 8, thus forming the fast and loose members of a friction clutch mechanism. The loose pulley 8 is mounted to rotate freely upon the shaft 5 and is movable axially of the shaft toward and from position to engage the fast member 6. An ear 9 on the frame of the machine provides a bearing for a rock shaft 16 having an arm 10 which is connected by a rod 14 to a foot treadle (not shown). The rock shaft has on its rear end an eccentric pin 18, which carries a shoe 15. The shoe stands in a groove 12 in the hub of the loose pulley 8, as shown in Fig. 6. The depression of the treadle partly rotates the shaft 16 in the bearing 9 thereby moving the shoe 15 by means of the eccentric pin 18 in the direction to force the loose pulley 8 into frictional engagement with the fast pulley 6. A spring pressed rod 20 which passes through a lug on the frame of the machine 25 acts on the arm 10 to return the loose pulley 8 to an inoperative position when the treadle is released.

Two arms 22, Fig. 4, extending upwardly from the head of the machine provide a bearing for the pivoted beater or hammer 24 and also a shoe guard. The hammer 24, Fig. 1, is in the form of an L-shaped lever having a beating face 25 at one end and pivoted near to its other end between the upwardly extending arms 22 by a pivot pin 28. A bifurcated member 30 pivoted to the lower end of the hammer 24 is connected to one end of a piston rod 32. This piston rod has a head portion 33 which is confined in a cylinder 34. Said cylinder is pivotally mounted at its rear end upon an eccentric or crank 39 on the shaft 5 by a plate 36 and bolts 37 shown in Fig. 3. Resilient material 40, which may be rubber in suitable form, is located in this cylinder on both sides of the head 33 of the piston and fills the spaces between said head and the end of the cylinder on one side and the head and an adjustable stopper on the other side. This resilient material completes an approximately positive connection between the crank shaft 5 and the hammer 24 but yieldingly restricts the reciprocation of the piston in the cylinder. By reason of its resilient qualities this material will yield to the piston sufficiently to compensate for such variations of the work as the hammer will encounter during the beating operation. The use of this yielding material also causes the hammer to deliver a light rebounding blow.

The machine frame is provided with a projecting bearing 42 to the outer end of which is connected the spindle 44 of the work support. The spindle 44 is shown as

made in two sections 44 and 46, the section 46 being formed as a sleeve pivoted at its lower end to the bearing 42 and threaded to receive the threaded lower portion of the spindle 44, the spring pin 47 in the sleeve 46 preventing accidental rotation of the jack. The spindle 44 is guided loosely through a bracket 48 which is adjustably secured in the frame by a binding screw 49. A hand wheel 50 mounted on the said spindle provides for vertical adjustment of the jack. A member 52 having a tubular portion adapted to fit over the upper end of the spindle and free to turn thereon has a pair of upwardly extending arms 54 which support a block 58 pivoted between the upper ends of the arms 54. The carriage 56 is mounted on the block 58 by a curved slot or guideway 59 for movement longitudinally of the shoe and carries a toe pad 60 and a heel post 62 to support a shoe on the last during the operation of the machine thereon. The toe pad 60 is mounted for vertical adjustment in the upper end of an arm 64 which is pivoted to the carriage at 65 below and back of the pad and has a spring pressed latch 66 which, operating with a ratchet plate 68 on the carriage, adjusts the rest 60 upwardly and backwardly, or reversely, with relation to the heel post 62 for different sizes of shoes. A thumb screw 70 provides vertical adjustment for the rest 60 in the arm 64 to bring the curvature of the shank of the shoe substantially parallel to the guideway 59 of the carriage so that the face of the hammer will not strike at an angle to the sole. The heel post 62 is mounted in a member 72, in which it is held by the split clamp and screw 79. The member 72 carries a stud 71 which is journaled in a part 77 for movement about an axis which extends longitudinally of the shoe. The part 77 lies between and is pivoted to ears 75 by a pin 73 which also engages a notch in the stud 71 to prevent withdrawal of the stud, the notch being shaped to permit a limited rotation of the stud 71 and hence a lateral movement of the post 62 about the stud as an axis to allow the shoe to be tilted at the proper angle for the hammer to conform the shank portion of the sole to the transverse curvature of the shank stiffener. A lug 74 depending from the heel pin supporting member 72 rests by a rounded face on a spring pressed plunger 76 in the carriage to keep the toe of the shoe pressed down upon the toe pad. Movement of the pin 62 by the plunger 76 is limited in one direction by contacting faces at 81 formed respectively upon the part 77 and the ears 75. The toe pad 60 is mounted for movement like the heel pin about an axis 61 extending longitudinally of the shoe and preferably substantially parallel to the bottom of the forepart thereof.

Having now described my invention, what

I claim as new and desire to secure by Letters Patent of the United States is:—

1. A shoe shank beating machine having, in combination, a beater having a plane beating face, a support by which a shoe on its last is movable about an axis extending longitudinally through the last to present to the beater either side of the shank of the shoe alternatively in such a plane that the beater will strike the shoe with a small component of movement directed inwardly away from the edge of the shoe and a large component directed perpendicularly to the side of the shank being beaten, and means for operating the beater to do its work. 70

2. A shoe beating machine comprising an angular beater having a horizontal arm provided with a relatively fixed beating face on its lower side and a vertical arm rigid with the horizontal arm and pivotally supported between its ends, a crank shaft, and a yielding connection between the crank shaft and the lower end of said vertical arm. 80

3. A shoe beating machine having, in combination, a beater comprising an angle lever having a horizontal arm provided with a beating face and a vertical arm pivotally supported between its ends, a piston pivoted to the lower end of said vertical arm, a crank shaft, a cylinder pivoted on the crank shaft and containing the head of the piston, and yielding packing material confined in the cylinder on opposite sides of the piston head. 90

4. A shoe beating machine having, in combination, a beater comprising an angle lever having a horizontal arm provided with a beating face and a vertical arm pivotally supported between its ends, a crank shaft, a yielding connection between said crank shaft and the lower end of said vertical arm, a continuously running driving pulley movable endwise along said crank shaft and turning freely thereon, a friction disk fast on the crank shaft, a rock shaft having an eccentric pin, a block carried by said pin and standing in a groove in the pulley, and a treadle connection to the rock shaft. 100

5. A shoe shank beating machine having, in combination, a beater comprising a rigid angle lever arranged with one arm horizontal and the other vertical and having a beating face on its horizontal arm, means for operating said lever, and a support for the shoe comprising a toe pad mounted to turn with the shoe about the longitudinal axis of the shoe and a heel pin and carrier supported to permit such turning movement of the shoe for presenting the two sides of the shank of the shoe alternatively in like relation to the beating face of the beater. 110

6. A shoe shank beating machine having, in combination, a beater comprising an

angle lever having one arm horizontal and the other vertical and having a beating face on its horizontal arm, means for operating said lever, and a support for the shoe comprising a carriage, a heel pin arranged to tip thereon with the shoe about the longitudinal axis of the shoe to permit the presentation of either of the sides of the shoe shank in operative relation to the beater, an arm pivoted to said carriage below the shoe and mounted to swing toward and from the heel pin, a spring latch for securing the arm in adjusted position, and a toe pad mounted on the arm for tipping movement with the heel pin and vertically adjustable with relation to the swinging arm. 75

7. A shoe shank beating machine having, in combination, a power operated beating member having a beating face which delivers a blow in a substantially constant horizontal plane and substantially perpendicular to the surface beaten, and a support for a shoe on its last constructed and arranged to permit movement of the shoe about an axis extending longitudinally of the shoe and through the material of the last whereby oppositely inclined sides of the shank portion of a shoe may be presented alternatively in parallel relation to the beating face. 95

8. A shoe shank beating machine having, in combination, a beater comprising an angle lever having a substantially horizontal arm provided with a beating face, means for giving the beater a movement to strike blows substantially perpendicular to said face, and a support for the shoe comprising a heel pin and a toe pad each arranged to tip with the shoe about an axis extending longitudinally of the shoe to enable the shoe to be presented with the plane of either of the inclined sides of the shank parallel to the plane of the beating face of the beater. 105

9. A shoe shank beating machine having, in combination, an angular beater; means for rapidly vibrating the beater to deliver to a shoe shank a succession of blows; and a connection between the beater and the vibrating means, including a piston and a cylinder in which the head of the piston is movable, and resilient material of slight compressibility confined between the piston head and an end wall of the cylinder in position to give a slightly yielding quality to the blows of the beater. 115

10. A shoe shank beating machine having, in combination, a beater, means for operating the beater to deliver a blow at a substantially fixed angle to the horizontal, toe resting means, a heel pin, and a clamp for the heel pin, said clamp being mounted for limited movement about an axis at right angles to the pin and extending in the di- 120 125 130

rection of the length of the shoe whereby the opposite sides of the shank of a shoe supported by said heel pin and toe resting means may be presented to the beater at the same angle laterally of the shoe to facilitate the formation of a cottage-roof shank by the action of the beater.

In testimony whereof I have signed my name to this specification in the presence of two subscribing witnesses.
